MAGNETIC SEPARATION OF POSITIVE AND NEGATIVE IGNITOR FIRING PULSES

Burnice D. Bedford, Scotia, N. Y., assignor to General Electric Company, a corporation of New York

Application April 25, 1955, Serial No. 503,695

11 Claims. (Cl. 315—252)

This invention relates to ignitor firing circuits for vapor electric discharge devices employing a pool-type cathode and an ignitor immersed therein for initiating the discharge of said device.

In order to obtain the desired precision of operation of the electric discharge devices of the type contemplated herein, a supply circuit is usually provided which impresses voltages of predetermined wave form, such as voltages of peaked wave form, on the ignitors or starting electrodes thereof. Only a small inverse voltage is permissible on the ignitors or starting electrodes of such discharge devices or they will either be destroyed or the life thereof will be materially reduced. As a consequence, it is common practice to couple the ignitors of the discharge devices to the supply circuit by means of a transformer, connecting each ignitor in series with a unidirectional current conducting device and connecting the series combination across the transformer output circuit. The unidirectional current conducting devices are poled to pass current in a direction to initiate discharge of the device and block or eliminate reverse current half cycles of the alternating current supply. The unidirectional current conducting devices are generally rectifiers of the selenium type which are subject to failure particularly if the rating of the rectifier is not high enough. Failure of the rectifiers result in either immediate destruction of the associated ignitor or a substantially reduced life thereof.

Since the rectifiers employed are subject to failure and since they are relatively expensive, particularly in the high rating groups, it is desirable to provide firing circuits wherein such rectifiers are not required. One such circuit is disclosed in the co-pending application of Harry L. Kellogg, Serial No. 266,526, filed January 15, 1952, now Patent No. 2,730,661, and entitled "Initiating the Arc in Mercury Pool Tubes" and which is assigned to the assignee of my present application. In most circuits devised to eliminate such blocking rectifiers, however, the output transformers used to supply the ignitor potential must be constructed of square loop magnetic material and narrow peak firing circuits must be used if the circuit is to be effective. Obviously, if the rectifier eliminating circuit is not effective the life of the ignitors of the electric discharge devices will have a short life. It is, of course, an added expense to construct the output transformers of a square loop magnetic material and it is also an added expense to provide firing circuits of the narrow peak type. This being the case, it may not be economically feasible to eliminate the rectifiers by the use of such equipment.

Accordingly, it is an object of this invention to provide an improved energizing circuit for starting electrodes of pool cathode type valves wherein the application of reverse voltages on the starting electrodes is substantially eliminated, which utilizes ordinary magnetic material in the magnetic core inductive devices employed, and wherein the firing potential applied is of a wave form having ordinary peak widths.

Another object of this invention is to provide an improved energizing circuit for starting electrodes of pool cathode type valves wherein the application of reverse voltages on the starting electrodes is substantially eliminated without the use of blocking rectifiers, wherein ordinary magnetic material is used for the magnetic cores of inductive devices employed, and wherein the wave form of the ignitor firing potential has peaks of ordinary widths.

5 10 Briefly stated, in accordance with the invention, the usual blocking unidirectional current conducting devices may be eliminated or the ratings of the rectifiers required are substantially reduced by providing saturable core impedance devices in the primary circuits of the ignitor potential supplying circuit which devices are saturated in such a manner as to pass positive firing peaks or half cycles and substantially reduce the magnitude of negative firing peaks or half cycles. In this way, the positive and negative ignitor firing pulses or peaks are separated by magnetic means.

15 20 The invention both as to its organization and method of operation will be better understood from the following description taken in connection with the accompanying drawing in which:

25 30 Fig. 1 is a schematic representation of a pair of mercury pool cathode discharge devices in their associated ignitor firing circuits, in which the invention in one of its forms is embodied; and

35 40 Fig. 2 is a schematic representation similar to the representations of Fig. 1 illustrating the invention in another of its forms.

In the circuits schematically represented in Figs. 1 and 2 of the drawing a pair of vapor electric discharge devices 10 and 11 employing pool type cathodes 12 and 35 ignitors 13 immersed therein for initiating the discharge of said device is used. The discharge devices 10 and 11 are also provided with anodes 10a and 11a, respectively. The cathode and anode circuits of these valves are not shown since the specific arrangement of their components forms no part of this invention but terminals C and A, respectively, are brought out to indicate the position of such connections. It will be understood, however, that the valves may be arranged to act as rectifiers in a well-known manner or they may be arranged to act 45 as inverters, which is also a well-known connection. In any case, the invention is applicable to the type valves contemplated herein when operated as either rectifiers or as inverters. Also, the invention is applicable to the use of single valve such as valve 10 or valve 11.

50 55 Referring particularly to Fig. 1, it will be seen that the energizing circuit for the ignitors 13 is supplied from an alternating current source 14. As illustrated a wave peaking circuit 15 is connected in series with a current limiting and blocking linear reactor 16 across the alternating current source 14 and a second wave peaking circuit 15a is connected in cascade with the first. The wave peaking circuits 15 and 15a are employed to provide an alternating current voltage of peaked wave form to be applied to the ignitors 13 of the valves 10 and 11. As 60 illustrated, each peaking circuit is of the type disclosed and claimed in U. S. Patent 2,431,903, granted December 2, 1947, on an application of E. F. W. Alexanderson and A. H. Mittag.

The wave peaking circuit 15 comprises a saturable 65 70 firing reactor 17, and a firing capacitance 18, which together constitute a resonant circuit of the non-linear type. That is, the circuit is non-linearly resonant with respect to the magnitude of the voltage of source 14, the inductive reactance of firing reactor 17 having a value which is substantially greater than the capacitive reactance of its supply circuit within the lower region of the source voltage, and smaller than the capacitive reactance thereof

within the upper region so that an impulse of voltage is produced when the firing reactor 17 saturates. These impulses occur twice during each cycle of voltage at times relative to the supply voltage wave which are determined by the saturation of a non-linear firing reactor 17. The linear reactor 16 is connected between the voltage source 14 and the peaking circuit 15 to prevent discharge of the capacitor 18 back to the voltage source and to limit the magnitude of the current derived from the supply.

The peaking circuit 15a has a firing reactor 17a and a capacitor 18a, which correspond in function to the like component 17 and 18 on the peaking circuit 15. The use of the two peaking circuits in cascade provides a better peaking. By better peaking, it is meant a circuit which supplies a wave form having narrower peaks. The output of the peaking circuit 15a is connected directly across the series combination of a primary winding 19 of an output transformer 20 and the main winding 21 of a saturable core impedance device 22. In addition, the peaking circuit 15a is connected across the series combination of the primary winding 23 of output transformer 24 and the main winding 25 of saturable core impedance device 26. That is, the two series circuits referred to are connected in parallel with each other and across the output of the peaking circuit 15a. The secondary or output winding 27 of the output transformer 20 is connected directly across the ignitor and cathode 13 and 12, respectively, of the valve 10 and the output transformer 24 has its secondary or output winding 28 connected to supply the ignitor potential to the ignitor 13 of the discharge device 11.

The saturable core impedance devices 22 and 26 have biasing windings 29 and 30, respectively. As indicated in Fig. 1, these biasing windings (29 and 30) are connected in series and are energized from a source of direct current indicated by the numeral 31. The direct current source 31 is preferably of sufficient magnitude to provide enough ampere turns to saturate each of the saturable impedance devices 22 and 26. The biasing windings are connected in the direct current circuit in such a manner that their magnetizing action on their respective reactors is to aid the magnetizing effect of a positive firing half cycle flowing in the main winding and oppose the magnetizing effect of a negative ignitor current.

Reactors 22 and 26, offer very little impedance to a positive firing current in their respective circuits since they are already saturated in an aiding direction but present a very high impedance to negative ignitor currents which tend to build up ampere turns in opposition to the established direct current ampere turns. Thus, currents which are of a sense to supply positive firing peaks in the circuits of the ignitors 13 of the two valves 10 and 11, respectively, will pass substantially unimpeded through circuits of the primary windings 19 and 23 of the ignitor potential supplying output transformers 20 and 24, respectively, while currents caused by negative firing potentials in the circuits of the valves will be suppressed or substantially eliminated by the saturable core impedance devices 22 and 26.

With the circuit just described, the magnetic separation of positive and negative firing pulses can be accomplished with relatively small reactors in series with the primary windings of each output transformer. If the series saturable core reactors 22 and 26 are made larger and the bias thereon made correspondingly larger, then these devices may be used to control the time of ignitor firing in the valve associated with the respective circuits as well as separating the positive and negative firing peaks. Also, one of the peaking circuits may be eliminated if the bias reactors 22 and 26 are made sufficiently large.

The circuits shown diagrammatically in Fig. 2 of the drawing are even more effective in separation of the posi-

tive and negative peaks with ordinary magnetic material in the output transformers and saturable core impedance devices than the circuit of Fig. 1. The elements of Fig. 2 which correspond to those of Fig. 1 are given like reference numerals for brevity of description.

The circuit of Fig. 2 also utilizes the source of alternating current 14, a linear blocking and current limiting inductor 16 in series therewith, a pair of cascade connected firing circuits 15 and 15a, and a pair of saturable core reactors 22 and 26 which have main windings 21 and 25, and biasing windings 29 and 30, respectively. It will also be seen that the biasing windings 29 and 30 are connected in the same manner as the biasing windings 29 and 30 shown in Fig. 1 across a direct current source 31.

In the embodiment of the invention illustrated in Fig. 2, saturable transformers 32 and 33 are provided to supply the ignitor potentials for the valves 10 and 11, respectively. The ignitor potential supplying transformers 32 and 33 are provided with primary or input windings 34 and 35, respectively, output or secondary windings 36 and 37, respectively, and separate biasing windings 38 and 39, respectively. Each primary winding is connected in series with the main winding of one of the individual saturable core impedance devices 22 and 26. That is, the primary winding 34 of the ignitor potential supplying transformer 32 is connected in series with the main winding 21 of the saturable core impedance device 22 and the primary winding 35 of the transformer 33 is connected in series with the main winding 25 of the saturable core impedance device 26. Each of these series circuits is connected across the output of the peaking circuit 15a and in parallel with each other.

Since the biasing windings 29 and 30 of the two saturable core impedance devices 22 and 26 are connected as described with reference to the circuit of Fig. 1, each of the saturable core impedance devices presents a very high impedance to a negative firing pulse in its series circuit and practically no impedance to a positive firing pulse therein. That is to say, the saturable core impedance devices 22 and 26, act to separate the positive and negative ignitor firing pulses as previously described. The biasing windings 38 and 39 on the output transformers 32 and 33 are provided to supplement this peak separating action.

As illustrated the saturable transformer biasing windings 38 and 39 are connected in series with each other across a direct current source 40. The biasing windings are wound on their cores in such a manner that their magnetizing action on their respective transformer cores is to aid the saturation of the core when a negative firing pulse is applied to the primary winding of the particular transformer. That is, the biasing windings 38 and 39 are wound on their respective transformer cores so that the magnetic effect of the current flowing in the biasing winding is to aid the magnetic effect of the current of a negative firing pulse in the primary winding and to oppose the magnetic effect of a positive half cycle of current flowing therein. In this way, the flux in each transformer will be changed substantially due to a positive half cycle of current from the circuit 15a while the flux would not change appreciably due to a negative half cycle of current from the peaking circuit 15a. Under these circumstances, positive firing potentials will be very effectively induced across the potential supplying transformer secondary windings while only a minimum negative firing potential can be.

It will be appreciated that a positive firing half cycle in the supply circuit of the valve 10, that is, in the circuit of the transformer 32, represents a negative firing half cycle in the supply circuit of the valve 11 and vice versa (in the circuit of the primary winding 34 of the transformer 33). With this arrangement, both the saturable core impedance device 22 and the saturable transformer 32 tend to eliminate negative firing potential on

the ignitor 13 of the valve 10 and both the saturable core impedance device 26 and the saturable transformer 23 cooperate substantially to eliminate the occurrence of a negative firing potential on the ignitor 13 of the valve 11. Due to the condition of their cores, however, none of the saturable impedance devices referred to tend to suppress or eliminate the positive firing potentials on the ignitors. Thus, with this arrangement a very effective magnetic separation of the positive and negative firing peaks is obtained.

Although I have described above particular embodiments of my invention, any modifications can be made, and it is to be understood that I intend to cover by the appended claims all such modifications as fall within the true spirit and scope of the invention.

What I claim as new and desire to secure by Letters Patent of the United States is:

1. In combination, an electric discharge device of the cathode pool type having a starting electrode, a transformer having a primary input winding to be energized with alternating current and a secondary output winding, and a saturable core impedance device having a main winding and a biasing winding, said main winding and said primary winding connected in series with each other, the circuit of said output winding of said transformer being connected across said starting electrode and cathode of said discharge device, the said biasing winding being adapted to be energized from a source of direct current, the magnetizing action of said biasing winding being sufficient to saturate said saturable impedance device, the magnetizing action of said main winding being to aid and oppose the magnetizing action of said biasing winding on alternate half cycles of said alternating current so that said saturable impedance device tends to pass and suppress current flow on alternate half cycles.

2. In combination, an electric discharge device of the cathode pool type having a starting electrode, a transformer having a primary input winding energized with alternating current, a secondary output winding connected to supply a starting potential to said starting electrode, and a biasing winding energized with direct current, the magnetizing action of said biasing winding being in opposition to the magnetizing effect of alternate half cycles of said alternating current, and a saturable core impedance device having a main winding and a biasing winding, said main winding and said primary winding being connected in series with each other, said biasing winding of said saturable core impedance device being energized from a source of direct current of sufficient magnitude that said biasing winding saturates said saturable impedance device and the magnetizing action of said main winding is to aid and oppose the magnetizing action of said biasing winding on alternate half cycles of said alternating current so that said saturable impedance device tends to pass and suppress current flow on alternate half cycles, the magnetizing effect of said transformer and saturable impedance biasing windings being to oppose the magnetizing effect of alternate half cycles.

3. A circuit for energizing the starting electrode of a cathode pool type electric discharge device, comprising a transformer having a primary input winding to be energized with alternating current and a secondary output winding interconnected with the starting electrode, and a saturable impedance device having a main winding and a biasing winding, said main winding of said saturable impedance device and at least a part of a winding of said transformer being connected in series circuit relationship with each other, said biasing winding of said saturable impedance device being energized with direct current, the magnetizing action of said biasing winding being in opposition to the magnetizing effect of alternate half cycles of said alternating current.

4. A circuit for energizing the starting electrode of a cathode pool type electric discharge device, comprising a

transformer having a primary input winding to be energized with an alternating current and a secondary output winding interconnected with the starting electrode, and a saturable impedance device having a main winding and a biasing winding, said main winding of said saturable impedance device being connected in series with said primary input winding, said biasing winding of said saturable impedance device being energized with direct current, the magnetizing action of said biasing winding being in opposition to the magnetizing action of alternate half cycles of said alternating current.

5. A circuit for energizing the starting electrode of a cathode pool type electric discharge device comprising a transformer having a primary input winding energized from an alternating current source, a secondary output winding interconnected with the starting electrode, and a biasing winding energized from a direct current source, the magnetizing action of said biasing winding being in opposition to the magnetizing effect of alternate half cycles of said alternating current, and a saturable impedance device having a main winding connected in series with said primary winding and a biasing winding arranged to be energized from a direct current source, the magnetizing effect of said biasing winding of said saturable impedance device being in opposition to the magnetizing effect of alternate half cycles of said alternating current, the magnetizing effect of said biasing windings of said saturable impedance device and said transformer being in opposition to alternate half cycles of said alternating current on their respective devices.

6. In combination, a pair of electric discharge devices of the cathode pool type having a starting electrode, said discharge devices being connected to conduct on alternating cycles of alternating current, a pair of transformers, each of said transformers having a primary winding connected to be energized from a source of alternating current energy and a secondary output winding connected to supply the starting electrode potential, and a pair of saturable reactance devices, each of said saturable reactance devices having a main winding connected in series with one of said transformer primary windings and a biasing winding, said biasing winding on each of said saturable impedance devices being connected across a source of direct current, said biasing windings being arranged in such a manner that their magnetizing action aids and opposes the magnetizing action of the current in the associated main winding on alternate half cycles so that each saturable impedance device tends to pass and suppress current flow on alternate half cycles.

7. In combination, a pair of electric discharge devices of the cathode pool type having a starting electrode, said discharge devices being connected to conduct alternate half cycles of alternating current, a pair of transformers, each of said transformers having a primary input winding connected to be energized from a source of alternating current, a secondary output winding connected to supply the starting electrode potential, and a biasing winding connected to be energized from a direct current source, the magnetizing action of said biasing winding being in opposition to the magnetizing action of alternate half cycles of said alternating current source and in opposition to the magnetizing effect of opposite half cycles with respect to each other, and a pair of saturable reactance devices, each of said saturable reactance devices having a main winding and a biasing winding, the main winding of each saturable reactance device being connected in series with one of said transformer primary windings, said reactance biasing winding being connected across a direct current source, said biasing windings being arranged in such a manner that their magnetizing action aids and opposes the magnetizing action of the current in the associated main winding on alternate half cycles so that each saturable impedance device tends to pass and suppress current flow on alternate half cycles and in such a manner that their magnetizing action opposes the magnetizing ac-

tion of the current in the associated primary winding on opposite half cycles.

8. In combination, a voltage peaking circuit for producing an alternating voltage which is symmetrical with respect to positive and negative half cycles and which is of peak wave form, an electric discharge device of the cathode pool type having a starting electrode, a transformer having a primary input winding connected to said peaking circuit for energization thereby and a secondary output winding connected to supply a potential to said starting electrode and a saturable reactance device having a main winding connected in series with said primary winding and in a biasing winding connected to be energized by a direct current source, the magnetizing action of said biasing winding being sufficient to saturate said saturable reactance device, the magnetizing effect of said main winding being to aid and oppose the magnetizing effect of said biasing winding on alternate half cycles of said alternating current source so that said saturable impedance device tends to pass and suppress the current flow on alternate half cycles.

9. In combination, a voltage peaking circuit for producing an alternating voltage which is symmetrical with respect to positive and negative half cycles and which is of peak wave form, an electric discharge device of the cathode pool type having a starting electrode, a transformer having a primary input winding connected to said peaking circuit for energization thereby, a secondary output winding interconnected with the starting electrode, and a biasing winding energized with direct current, the magnetizing action of said biasing winding being in opposition to the magnetizing action of alternate half cycles of said alternating current, and a saturable reactance device having a main winding connected in series with said primary input winding and a biasing winding connected to be energized with direct current, the magnetizing action of the biasing winding of said saturable reactance device being sufficient to saturate said saturable reactance device and of a sense to aid and oppose the magnetizing effect of said main winding on alternate half cycles of said alternating current so that said saturable reactance device tends to pass and suppress current flow on alternate half cycles, the magnetizing effect of said transformer biasing winding and said saturable reactance biasing winding opposing the magnetizing action of alternate half cycles of said alternating current in their associated places.

10. In combination, a voltage peaking circuit for producing an alternating voltage which is symmetrical with respect to positive and negative half cycles and which is of a peaked wave form, a pair of electric discharge devices of the cathode pool type having a starting elec-

trode, said discharge devices being connected to conduct alternate half cycles of alternating current, a pair of transformers, each of said transformers having a primary input winding connected to said peaking circuit for energization thereby and a secondary output winding interconnected with said starting electrode, and a pair of saturable reactance devices, each of said saturable reactance devices having a main winding and a biasing winding, the main winding of each of said saturable reactance devices being connected in series with one of said primary input windings, each of said biasing windings being connected to be energized by a source of direct current, said biasing windings being arranged in such a manner that their magnetizing effect aids and opposes the magnetizing effect of the current in the associated main winding on alternate half cycles so that each saturable reactance device tends to pass and suppress current flow on alternate half cycles.

11. In combination, a voltage peaking circuit for producing an alternating voltage which is symmetrical with respect to positive and negative half cycles and which is of a peaked wave form, a pair of electric discharge devices of the cathode pool type having a starting electrode, said discharge devices being connected to conduct alternate half cycles of alternating current, a pair of transformers, each of said transformers having a primary input winding connected to said peaking circuit for energization thereby, a secondary output winding interconnected with the starting electrode, and a biasing winding energized with direct current, the magnetizing effect of said biasing winding being in opposition to the magnetizing effect of alternate half cycles of said alternate current, and a pair of saturable reactance devices, each of said saturable reactance devices having a main winding, a biasing winding, a main winding of each saturable reactance device being connected in series with one of said primary input windings, said biasing windings on each of said saturable impedance devices being connected across a direct current source, said reactance biasing windings being arranged so that their magnetizing action aids and opposes a magnetizing action of current in the associated main winding on alternate half cycles so that each saturable impedance device tends to pass and suppress the current flow on alternate half cycles, the magnetizing action of each reactance biasing winding and the transformer biasing winding of the transformer in series circuit relationship with the individual saturable reactance device opposing the magnetizing action of current in the associated device on alternate half cycles.
